YARN GUIDE MEANS

Frank G. Weisbecker, Glenside, Pa., assignor to
Hosiery Patents Inc., Lansdale, Pa., a corpora-
tion of Pennsylvania

Application July 29, 1943, Serial No. 496,668

7 Claims.

(Cl. 66—126)

This invention generally relates to yarn guide means for textile machines and the like, and more particularly to the type comprising a releasably mounted yarn guide element, or tube.

In textile machines, such as straight knitting machines of the type commonly utilized for producing full-fashioned hosiery fabrics, the knitting yarn is fed to the knitting elements by selectively reciprocated yarn laying devices, or carriers. A modern carrier of this type is provided with a releasably mounted yarn guide element, usually in the form of small rigid, or resilient yarn guide tube of metal or other material. The yarn passes through this tube, and from one tip thereof directly to the needles of the knitting machine. To facilitate the replacement of these yarn guide tubes when they become defective, the carriers and their associated tubes usually have added thereto complementary securing, or latching elements, in one form or another, which releasably retain the tubes in determined position on the carriers. Due to the small and rather delicate nature of these elements, it has long been recognized that their provision and use involve manufacturing costs, as well as structural and functional difficulties, which are more or less detrimental from a commercial and practical standpoint.

One object of my invention is to provide novel yarn guide means of the indicated type, which is free of the referred to added securing or latching elements, and the attendant manufacturing costs and difficulties associated with their provision and use.

Another object is to provide such means having a yarn guide element with a resilient yarn guide section arranged to be releasably maintained in cooperative association with its support by a novel tube holding action.

Another object is to provide such means having a yarn guide element with a resilient yarn guide section arranged to perform the dual function of guiding the yarn and releasably retaining the element in cooperative association with its support.

A further object is to provide such means having a yarn guide element, or tube, with a resilient upper, and a resilient lower section, one of which sections is arranged to releasably retain the element in cooperative association with its support, while the other section is arranged to be flexed when striking an obstruction.

It is also an object to provide such means in which the yarn guide element, or tube, can be quickly and easily connected with, or discon-

nected from, its support, by bodily moving the element in a sidewise, or lateral direction only, during such action.

Another object is to provide such means having a yarn guide element with a resilient yarn guide section arranged to be releasably associated with a support by means maintaining said section in tensioned, flexed, or offset position on the support.

10 A still further object is to provide novel yarn guide means for textile machines and the like, comprising a plain tubular yarn guide element, having a curved, or offset, resilient yarn guide section.

15 A further object is to provide novel yarn guide mounting means for textile machines and the like, which is adapted to releasably retain in determined position, a plain tubular yarn guide element having a resilient yarn guide section located in the upper portion thereof arranged to have tensioned engagement with the support, and a resilient lower end portion adapted to be flexed when it strikes an obstruction.

Another object is to provide such yarn guide 25 mounting means having a readily accessible longitudinally extending groove in the front surface thereof for receiving and releasably seating a yarn guide tube; the groove being arranged so that a yarn guide tube can be placed therein or removed therefrom by a lateral movement of the tube.

An additional object is to provide a novel yarn 30 laying device, or carrier, for straight, or full-fashioned knitting machines, which embodies the said and other structural and functional features of advantage over similar devices of the prior art.

With these and other objects in view, which will become readily apparent from the following detailed description of the practical illustrative embodiments of my novel yarn guide improvements, shown in the accompanying drawings, the invention comprises the new elements, features of construction and arrangement of parts in cooperative relationship, as herein disclosed and more particularly pointed out in the appended claims.

In the drawings:

Figure 1 is a front elevational view, on an enlarged scale, of the lower end of a conventional yarn carrier of the reciprocal type associated with straight, or full-fashioned knitting machines, and illustrates the embodiment therein of one practical form of my invention.

55 Fig. 2 is a view similar to Fig. 1 and illustrates

the application of another embodiment of my invention to a knitting machine yarn carrier of the said conventional type.

Fig. 3 is a view similar to Fig. 1, but with the yarn guide element shown in the latter omitted in Fig. 3.

Fig. 4 is an elevational view of the resilient yarn guide element shown in Fig. 1, as it appears when in normal, or released condition.

Fig. 5 is a view similar to Fig. 2, but with the yarn guide element shown in the latter, omitted.

Fig. 6 is an elevational view of the resilient yarn guide element disclosed in Fig. 2, as it appears when in normal or released condition.

Fig. 7 is a cross-sectional view taken substantially as indicated by the arrows 7-7 on Fig. 1.

Fig. 8 is a cross-sectional view taken substantially as indicated by the arrows 8-8 on Fig. 2.

Fig. 9 is a cross-sectional view taken substantially as indicated by the arrows 9-9 on Fig. 1.

Fig. 10 is a cross-sectional view taken substantially as indicated by the arrows 10-10 on Fig. 2.

Fig. 11 is a front elevational view, similar to Fig. 3, of a modified form of the yarn guide mounting construction of my invention associated with a knitting machine yarn carrier.

Fig. 12 is a cross-sectional view taken substantially as indicated by the arrows 12-12 on Fig. 11.

Fig. 13 is a front elevational view, similar to Fig. 11, but of another modified form of the knitting machine yarn guide mounting construction of my invention.

Fig. 14 is a cross-sectional view, taken substantially as indicated by the arrows 14-14 on Fig. 13.

Fig. 15 is a front elevational view, similar to Fig. 1, and illustrates an additional embodiment of my invention associated with a knitting machine yarn carrier.

Fig. 16 is a view similar to Fig. 15, but with the resilient yarn guide element, or tube, omitted.

Fig. 17 is an elevational view of the resilient yarn guide element, or tube, shown in Fig. 15, as it appears when in normal, or released condition.

In order that the broader aspects of my invention may not be overlooked when considering the specific exemplifications thereof hereinafter described, it is preliminarily pointed out that a unique feature of the invention resides in the utilization of a novel yarn guide element, or tube, having a special or resilient yarn guide section which lends itself to the performance of the dual function of guiding the yarn and releasably retaining the element in cooperative association with its support. To accomplish such dual functioning of the special section, various mounting or supporting means may be provided and arranged to cooperate with said section in such manner that its normal configuration or shape will be affected or altered after the yarn guide element is seated in determined position on the support. The alteration in the configuration of the resilient section is such as to develop a binding or holding action of sufficient intensity to maintain the section (and consequently the entire yarn guide element) in releasable position on its support against any element displacing force resulting from the operation of the machine on which the element is mounted. However, this binding or holding action is attained in such manner as to readily permit the element to be manually

withdrawn or released from its support, when desired, for replacement or other purposes.

In the drawings and description, various practical embodiments of my invention are disclosed for illustrative purposes in association with a well-known yarn laying device for a straight or full-fashioned knitting machine, and consequently, only those parts of such a conventional yarn laying device, or carrier, as are necessary to a complete understanding of the invention, have been included; for further information concerning the construction, operation, characteristics and use of such typical carriers, and their constituent parts, reference may be had to the following, or other, U. S. patents relating to this art:

Number	Date	Inventor
2,014,341	Sept. 10, 1935	F. G. Weisbecker.
2,101,801	Dec. 7, 1937	Do.
2,214,712	Sept. 10, 1940	Do.
2,218,976	Oct. 22, 1940	Do.
2,218,977	Oct. 22, 1940	A. L. Weisbecker.

2,317,318	Apr. 20, 1943	F. G. Weisbecker.

Reference may also be had to the various catalogs, or other literature, relating to full-fashioned knitting machines and their parts, published and copyrighted from time to time by the Textile Machine Works, of Wyomissing, Pa.

In general, the yarn guide means, of Figs. 1, 3, 4, 7 and 9 of the drawings, comprise a yarn guide element support in the form of a conventional yarn carrier arm 20 of the type ordinarily associated with straight or full-fashioned knitting machines, the illustrated lower end of which is modified in accordance with my invention; and a plain tubular or cylindrical yarn guide element 21 having a special or resilient yarn guide section 21a.

The yarn guide section 21a, of the tube 21 may be made resilient in accordance with the various resilient tube constructing practices of the above noted patents. If desired, and as shown, the entire tube may be made resilient by forming the same of coiled flat wire, or metallic ribbon of rectangular cross-section or of a combination flat and round wire, as taught by Patents Nos. 2,101,801, 2,218,977 and 2,317,318. The coiled metallic ribbon or wire may be formed of any suitable metal, such as "stainless" steel. In this connection it will be understood that when the section 21a, or the entire tube construction 21 is made in accordance with the practice of the said patents, the respective tube securing or latching elements disclosed in said patents are omitted in accordance with my invention, so that the resultant tube will be of a plain cylindrical configuration as more particularly illustrated by Fig. 4, or of a slightly tapered configuration, as shown in Figs. 15 and 17. If desired, a rigid apertured tip 21b of wear resistant metal, such as "carboloy" may be added to the lower end of the tube 21, by welding, as explained in Patent No. 2,218,977, or in other suitable manner.

The upper resilient yarn guide section 21a of the tube 21, is utilized to perform the dual function of guiding the yarn which passes therethrough and of releasably maintaining the tube 21 in cooperative association with its support. To perform the latter function, the section 21a is seated on its cooperating support or yarn carrier arm 20 in a tensioned, flexed or offset condition so as to develop a binding or holding action

of sufficient intensity to releasably maintain the tube in determined position on the support. The disclosed lower end of the conventional yarn carrier arm 20 is modified so as to provide such seating means for the tube section 21^a.

To facilitate an understanding of the changes or additions made in the lower end of carrier arm 20 in accordance with my invention, the conventional or prior art features of the latter will first be briefly pointed out. Following the prior art practice, the yarn carrier arm 20 is tapered longitudinally so that its thinnest portion is at the end adapted to support the yarn guide tube 21. This end of the carrier is also tapered to its opposite side edges, substantially as shown in Figs. 7 and 9. The thickness of the carrier end 20 may be substantially the same, or slightly greater along its longitudinal center line, than the external diameter of the tube 21, depending upon the number of yarn carrier arms operating in a given knitting machine section, and consequently the space available to permit the individual carrier arms to freely pass each other during their yarn laying operation.

Conventional straight, or full-fashioned knitting machines have as many as seven or nine yarn carriers 20 operating in closely spaced relationship in each knitting section producing a single flat stocking fabric, or blank, and such carriers travel in closely spaced parallel paths, each of the carriers having a reciprocating movement in a sidewise direction.

As shown in Figs. 1 and 3, the extreme lower edge 22 of the carrier arm 20 is curved as usual to provide space for free flexing movement of the protruding end of the resilient lower end of yarn guide tube 21. In the event the projecting tube end, including the tip 21^b, strikes an obstruction during use of the carrier as indicated, the projecting tube end yields due to the flexibility of the lower portion of the element 21. When the obstruction is passed, the deflected tube end will return to its normal straight yarn feeding position due to the resiliency of the lower portion of the element 21.

To guide the yarn into the upper end of the tube 21, the front face of the carrier arm 20 is provided with a yarn guide groove 23.

In accordance with my invention, the yarn carrier arm 20 of the general construction just described, is provided with mounting means for the tube 21, comprising a pair of spaced longitudinally aligned tube section seating grooves 24 and 25, and an intermediate element 26 adapted to tension, flex, or offset, the normally straight resilient tube section 21^a as shown in Fig. 1. The tube 21 is mounted on carrier 20 by laterally moving the tube into the seating or positioning grooves 24 and 25 so that section 21^a is tensioned, flexed, or offset by the element 26 to such an extent as to be securely, but at the same time releasably held on the carrier 20. Movement in a longitudinal as well as lateral direction is resisted by a combination frictional binding and detent action. The pressure developed by the resilient tube section 21^a on the element 26 effects a frictional binding action against longitudinal, as well as lateral movement of the tube, and the projection of the element 26 into the displaced portion of section 21^a simultaneously effects a detent action preventing longitudinal movement of the element 21. The latter action also results from the location of the curved resilient tube section 21^a intermediate the two straight tube

seating grooves 24 and 25, since this arrangement similarly prevents longitudinal movement of the tube. In other words, the tube 21 is firmly held in its determined position against the longitudinal and lateral displacing forces, or shocks, resulting from operation of the machine on which the carrier 20 is mounted. However, the tube holding or securing forces can be overcome by exerting a certain releasing pull on the tube in a lateral direction opposite to the direction in which the tube is moved when mounting it on the carrier 20, to effect bodily withdrawal of the tube from the forward, or open front portion of its positioning or seating grooves 24 and 25. When the tube is released from the arm 20, the section 21^a, due to its resiliency, will return to the straight line position shown in Fig. 4, so that all the sections of the tube will again be in longitudinal alignment, as before.

20 The element 26 may be integrally formed on the carrier 20 by punching, or otherwise providing an aperture 27 in the latter having the configuration shown in Fig. 3. The element 26 is preferably, but not necessarily, curved in such manner that the tube portion 21^a will contactingly rest against its adjacent surface when the tube 21 is in its cooperative position on the carrier 20, as shown in Fig. 1. The side wall 27^a of the aperture 27, which is directly opposite to the element 26, is so shaped and spaced from the adjacent side wall of the tube section 21^a as to permit the insertion of a tube engaging means, or tool, between the wall 27^a and said section, to facilitate positioning, or removal of the tube 21.

25 Since the modification of my invention illustrated by Figs. 2, 5, 6, 8 and 10, differs only in certain respects from the construction shown in Figs. 1, 3, 4, 7 and 9, the use of corresponding reference characters, to designate corresponding parts, will be resorted to so as to avoid repetition of the description of such parts.

30 The lower end of the carrier 20, shown in Figs. 2, 5, 8 and 10 is of a somewhat different conventional shape than that shown in Figs. 1, 3, 7 and 9. However, this is merely to illustrate that my invention is not limited in its application to one standard form of carrier. Insofar as my invention is concerned, the results are the same whether applied to one or another of such conventional carriers.

35 As in the case of the carrier 20 of Figs. 1 and 3, the extreme lower edge of the carrier shown in Figs. 2 and 5 is so shaped and situated relative to the resilient projecting end of the yarn guide tube 21, as to permit free flexing action thereof when it strikes an obstruction. However, if it is desired to provide a rigid projecting tube end, in place of the resilient tube end section shown in Fig. 2, the bottom edge of carrier 20 can be located somewhat closer to the bottom tube tip.

40 Instead of forming the element 26 of the first described form of my invention integral with the carrier 20, a separate element 28 is shown as provided on the resilient tube section 21^a of Figs. 2, 6 and 10. The aperture 27 of Figs. 2, 5 and 10 has a straight side wall 27^b which forms a continuation of the corresponding side walls of grooves 24 and 25. The flat outer portion of element 28, on the resilient tube section 21^a is arranged to rest against, or engage the wall 27^b when the tube is in determined cooperative association with its carrier 20. This will effect the tensioning, flexing, or offsetting of the tube section 21^a, as before. The binding or holding ac-

tion of the tube section 21^a, in this arrangement of my invention, is in effect substantially the same as that previously described.

The element 28, may be secured to the outer wall of the resilient tube section 21^a by soldering, welding, or in other suitable manner.

Figs. 11, 12, 13 and 14 disclose further modifications of the carrier construction 20 shown in Figs. 1 and 3, which may be utilized, if desired, in conjunction with the tubular yarn guide element of Fig. 4. Since the carrier constructions of Figs. 11, 12, 13 and 14 differ only in certain respects from that of Figs. 1 and 3, the corresponding parts of each are again designated by similar reference characters.

In the construction of Figs. 11 and 12, the element 26 is provided with a longitudinally grooved seat portion 29 for the resilient section 21^a of the tube 21, shown in Fig. 4. This seat portion 29 functions to keep the resilient section 21^a of the tube 21 in the same vertical plane as the adjacent sections of the tube positioned in the straight and aligned seating grooves 24 and 25. The portion 29 also functions as a detent means to prevent the section 21^a, and consequently the tube 21, from being accidentally displaced laterally from the front or open section, of its seating means on the carrier 20.

Figs. 13 and 14 illustrate a carrier construction such as shown in Figs. 1 and 3, however, provided with a continuous tube seating groove 31 of uniform width, having an offset portion 32 intermediate its ends. Such a carrier construction can also be utilized in conjunction with the yarn guide tube of Fig. 4, to releasably hold the latter in the determined cooperative position on the carrier, as previously described.

Figs. 15, 16 and 17, illustrate another modification of my invention, and one in which the support, or carrier construction is generally the same as that shown in Figs. 13 and 14. However, the tube receiving and seating groove 33 of Figs. 15 and 16 is straight, slightly tapered and of such width throughout, as to snugly accommodate therein a tube section of similar configuration and slightly lesser width.

Fig. 17 shows the normal configuration of a yarn guide tube 41 adapted to be cooperatively associated with the carrier 20 of Figs. 15 and 16. The tube 41 is of the resilient type constructed in accordance with the general practice followed in forming the tube of Fig. 4 and the disclosure of the hereinbefore listed patents. However, the upper resilient section 41^a of the tube 41 is bent or curved, substantially as shown in Fig. 17. When the tube 41 is placed in its seating groove 33 on the carrier 20 (see Fig. 15) in such manner that the curved resilient tube section 41^a is placed between the straight side walls of the groove, the section 41^a is straightened and the spring tension developed therein as a consequence of this action effects a side pressure between the tube section 41^a and the side walls of the groove 33 resulting in a frictional binding, or holding force, which accomplishes the same practical results pointed out in connection with the previously described embodiments of my invention.

It is to be particularly noted that the various embodiments of my invention involve a yarn guide element, or tube, of extreme simplicity, and that the preferred tube structures of Figs. 4 and 17 are devoid of any securing or latching

elements of the type heretofore associated with similar yarn guide tubes of the prior art. It is also to be noted that the cooperating supporting means for such plain tubular yarn guide elements or tubes involves an equally simple arrangement in comparison with the prior art structures, and one which provides the unique advantage of permitting cooperative association of the yarn guide element with its support, or release therefrom, by a short lateral movement of the element in each instance.

Of course, the yarn guide means herein disclosed can be changed and modified in various ways without departing from the invention more particularly defined by the appended claims.

I claim:

1. In combination, a support, a yarn guide element having a resilient yarn guide section, and means on said support arranged to releasably retain said element in cooperative association with said support when the element is bodily moved laterally into engagement with said means.

2. A yarn guide device for a knitting machine comprising in combination, a yarn guide support adapted to be mounted on said machine and having a straight yarn guide tube receiving groove with an offset portion intermediate its ends; and a yarn guide tube having a normally straight resilient yarn guide section releasably mounted in said groove in such manner that the resilient section of the tube is positioned in the offset portion of said groove.

3. A yarn guide device for a knitting machine comprising in combination, a yarn guide support adapted to be mounted on said machine and having a straight yarn guide tube receiving groove with an offset wall section at one side thereof intermediate its ends; and a yarn guide tube having a resilient yarn guide section with a surface projection, releasably mounted in said groove in such manner that the said surface projection is positioned in the yarn tube receiving groove at a point opposite to the offset wall section of the latter.

4. A yarn guide device for a knitting machine comprising in combination, a support for a yarn guide element, a yarn guide element having a resilient yarn guide section, and means on said support arranged to releasably retain said element in cooperative association with said support when the element is bodily moved laterally into engagement with said means.

5. In combination, a support provided with yarn guide element receiving means, a yarn guide element having a normally curved resilient yarn guide section, and means arranged to releasably maintain said section in straight position in the yarn guide receiving means.

6. In combination, a support provided with yarn guide tube receiving means, a yarn guide tube having a normally curved resilient yarn guide section, and means arranged to releasably maintain said section in substantially straight position in the yarn guide tube receiving means.

7. A yarn guide device for a knitting machine comprising in combination, a support, a yarn guide tube having a resilient yarn guide section, and means on said support arranged to releasably retain said tube in cooperative association with said support when the resilient yarn guide section is moved laterally into engagement with said means.

FRANK G. WEISBECKER.
